Primary Examiner — Ricky Pham*(74) Attorney, Agent, or Firm* — Cook Alex Ltd.; R. Blake Johnston(57) **CLAIM**

The ornamental design for a blender, as shown and described.

DESCRIPTION

FIG. 1 is a perspective view of the blender;
FIG. 2 is a right side elevational view of the blender;
FIG. 3 is a left side elevational view of the blender;
FIG. 4 is a front elevational view of the blender;
FIG. 5 is a rear elevational view of the blender;
FIG. 6 is a top plan view of the blender;
FIG. 7 is a bottom plan view of the blender;
FIG. 8 is a perspective view of the blender base, shown without the container for completeness of disclosure;
FIG. 9 is a right side elevational view of the alternative embodiment of the blender;
FIG. 10 is a left side elevational view of the alternative embodiment of the blender;
FIG. 11 is a front elevational view of the alternative embodiment of the blender;
FIG. 12 is a rear elevational view of the alternative embodiment of the blender; and,
FIG. 13 is a top plan view of the alternative embodiment of the blender, the bottom side of which is identical to FIG. 7. The broken lines shown in the drawings are for illustrative purposes only and form no part of the claimed design.
